5 Claims. (Cl. 66—89)

My invention relates to method of and apparatus for casting on loops on flat knitting machines. It is an object of my invention to obtain strong selvedge loops without waste of thread.

To this end the thread in the casting-on operation is put to the penultimate needle of the loops to be cast on and then formed into a firm selvedge loop round the last needle.

10 This is effected by deflecting the penultimate needle from the locking-in position when the needle is raised for putting the thread to it. By these means the thread is brought to lie unsunk on the hook side of the penultimate needle and on the opposite side of the last needle.

15 On account of this position of the thread on the penultimate needle an unsunk loop is formed which, like the sunk loops of the other needles, is knocked over when the next row of loops is formed. However, as the length of the thread in the unsunk loops is less than in the sunk loops, firm selvedge loops are formed without surplus thread.

20 In the drawings affixed to this specification and forming part thereof a machine in which my method may be performed, and various stages of operation are illustrated diagrammatically by way of example.

25 In the drawings
30 Fig. 1 is a partly sectional elevation showing part of a flat knitting machine.

Fig. 2 is a section on the line II—II in Fig. 1.

35 Figs. 3 and 4 are details showing the mechanism for operating the pressers, in two positions, drawn to a larger scale and in section.

40 Figs. 5 to 7 are diagrams showing the position of the needles.

45 Figs. 8 to 12 are diagrams showing various stages in the knitting of a fabric, and

50 Fig. 13 shows a finished fabric.

Referring now to the drawings, and first to Figs. 1 and 2, 21 is a frame of the machine, with an upper longitudinal beam 26 and a lower longitudinal beam 28. Mounted on the upper beam 26 is a support 29 for the thread guide rails 30 and 31 is one of the thread guides partly broken away.

55 21 is a cam shaft in the frame 27, 22 is a cam and 23 is a circular disc on the shaft, 13 is a shaft at the rear of the frame, which extends in parallel to the crank shaft 21, 14 is a rocking lever on the shaft 13, 15 is a pin at the free end of the rocking lever 14, 16 is a roller adapted to cooperate with the cam 22 and the disc 23, which

bar which is mounted to slide in the frame 27, 19 is a rod on the bar, and 20 is a fork at the inner end of the rod which engages in the boss of the roller 16. By shifting the bar 18 the roller 16 is alternately moved into active position to the cam 22 and the disc 23. 24 is a downward extension of the rocking lever 14 and 25 is a screw in the lower end of the extension 24 which serves as an abutment against the bar 18 for limiting the movement of the lever 14 with respect to 10 the cam 22.

15 12, 12 are arms or cranks on the shaft 13, 6 is a shaft which is mounted in suitable bearings 5 on the upper bar 26, 10 are arms or cranks arranged on the shaft, and 11 are connecting rods 15 extending from the arms or cranks 12 on the shaft 13 to the arms or cranks 10 on the shaft 6.

20 It will appear that when the bar 18 is shifted to move the roller 16 into active position with respect to the cam 22 on the shaft 21, the lever 14 is rocked and its rocking movement is communicated to the shaft 6 by the mechanism described. The extent to which the lever 14 follows the cam 22 in downward direction is determined by adjusting the screw 25.

25 Referring now to Figs. 3 and 4, 7 are sets of presser bars the position of which with respect to the arms or cranks 10 on the shaft 6 is indicated in Fig. 1, and 2 are pressers for cooperating with the needles 1. 4 is a slotted bracket in 30 which the presser bars 7 are mounted to slide, 8 is a notch in each presser bar, and 9 is an arm on the shaft 6 which engages the notch. 8 are the sinkers which are also mounted to slide in the bracket 4.

35 Referring now to Fig. 5, when it is desired to cast on a selvedge loop the corresponding thread is moved beyond the needle *a* at the selvedge for two more needles *b* and *c*. When the needles are in their lowest position the penultimate needle *b* is bent out of its normal position by the advancing presser bar 7 while the selvedge needle *a* and the last needle *c* remain in their normal position. When the needles are raised the newly laid thread 32 is placed on the hook side of the penultimate needle in floating condition. When the needles have almost completed their upward stroke the needle *b* is released by its presser bar and presser and allowed to return into its normal position as shown in 50 Fig. 7. In the upper final position of all needles the thread 32 is positioned on the needle *b* at the same side as on the selvedge needle *a* and is placed about the needle *c* in unsunk condition.

55 Fig. 8 is a perspective illustration showing the

position of four needles including the needles *a*, *b*, *c* after the thread guide has moved on to the left for beginning a new row of loops. When this sunk thread has been locked in hooks of the 5 descending needles, as shown in Fig. 9, and when it is knocked off, there are loops on all needles in row VI, Fig. 10, and the knitting is now continued in the usual manner, Fig. 11. As will appear from Fig. 12, the forming of the selvedge 10 loops on the penultimate needle *b* is improved by avoiding an unduly large pre-sunk loop, and at the same time the selvedge loops also draw tight sooner.

The finished fabric is shown in Fig. 13. 15 The device for deflecting the needles *i* acts as follows:

If loops are to be cast-on, the bar *18* is moved to the left so that the roller *16* is placed opposite the cam *22*, whereupon the shaft *6* is actuated in the manner described.

A presser bar *7* is arranged in front of each second presser *2* so that each second needle *i* is deflected from its normal position by the corresponding presser bar *7* and presser *2*. By this deflection of the needles *i* the thread is positioned on the needles in the manner desired.

For casting-on loops one needle only is to be deflected at each side of the fabric. The deflection of the other needles has no influence whatever upon the knitting process. As the presser bars *7* are, as shown in Fig. 1, at both sides of the knitting machine in a width corresponding to the desired widening of the fabric only, the first presser bar alone will act as a rule in the first instance. The deflection of the needles outside the fabric has no influence whatever as after the return of the presser bars the needles *i* return into their original position. At each successive casting-on the next presser bar comes, 40 with regard to the penultimate needle of the fabric, into a position adapted to effect casting-on. Then the deflected needles within the body of the fabric remain without influence as they are returned into their original position at the 45 next sinking operation.

I claim:—

1. The method of casting on loops on flat knitting machines comprising putting the thread 50 without sinking to the penultimate needle in the row in which a loop is cast on by deflecting the needle from its locking-in position as it rises, and laying the thread around the last needle as a selvedge loop with the thread lying on the hook side of the penultimate, and on the opposite side of the last needle.

2. An apparatus for casting on loops on flat knitting machines, comprising needles, a movable presser for each of said needles, a slotted bracket extending across the entire width of the 60 machine, sinkers adapted to slide in said bracket, presser bars one in front of each second presser also adapted to slide in said bracket and arranged in two groups, one at each end of the needle bank, and means for selectively operating said presser bars to deflect said pressers and thereby said needles during upward movement from their locking-in position into a position for laying the thread.

3. An apparatus for casting on loops on flat knitting machines, comprising needles, a movable presser for each of said needles, a slotted bracket extending across the entire width of the machine, sinkers adapted to slide in said bracket, 5 presser bars one in front of each second presser also adapted to slide in said bracket and arranged in two groups, one at each end of the needle bank, a rocking shaft mounted above said bracket, arms fixed to said rocking shaft and engageable with said presser bars, cranks fixed on said rocking shaft, a second rocking shaft mounted in the frame of the machine, links connecting said cranks and said second rocking shaft, a driving shaft also mounted in the frame of 10 said machine and means for translating the rotation of said driving shaft into rocking movement of said second rocking shaft.

4. An apparatus for casting on loops on flat knitting machines, comprising needles, a movable presser for each of said needles, a slotted bracket extending across the entire width of the machine, sinkers adapted to slide in said bracket, 20 presser bars one in front of each second presser also adapted to slide in said bracket and arranged in two groups, one at each end of the needle bank, a rocking shaft mounted above said bracket, arms fixed to said rocking shaft and engageable with said presser bars, cranks fixed on 25 said rocking shaft, a second rocking shaft mounted in the frame of the machine, links connecting said cranks to said second rocking shaft, a driving shaft also mounted in the frame of the machine, a cam on said driving shaft, a circular disk mounted on said driving shaft at 30 the side of said cam, a lever fixed to said second rocking shaft, and having a depending arm carrying an adjusting screw, a pin carried by said lever, a roller slidably arranged on said pin, and means for moving said roller alternately 35 into registering position with respect to said cam and said disk.

5. An apparatus for casting on loops on flat knitting machines, comprising needles, a movable presser for each of said needles, a slotted bracket extending across the entire width of the machine, sinkers adapted to slide in said bracket, 45 presser bars one in front of each second presser also adapted to slide in said bracket and arranged in two groups, one at each end of the needle bank, a rocking shaft mounted above said bracket, arms fixed to said rocking shaft and engageable with said presser bars, cranks fixed on 50 said rocking shaft, a second rocking shaft mounted in the frame of the machine, links connecting said cranks to said second rocking shaft, a driving shaft also mounted in the frame of the machine, a cam on said driving shaft, a circular disk mounted on said driving shaft at the side of 55 said cam, a lever fixed to said second rocking shaft and having a depending arm carrying an adjusting screw, a pin carried by said lever, a roller slidably arranged on said pin, a shaft slidably arranged in the frame of the machine, a lever arm fixed on said slide shaft, and a 60 fork at the free end of said lever arm adapted to engage said roller.

WOLDEMAR HEINITZ.
